UNITED STATES PATENT OFFICE.

MORRIS PEAK AND JAMES B. CASADAY, OF COLORADO SPRINGS, COLORADO.

GATE-HANGER.

SPECIFICATION forming part of Letters Patent No. 427,439, dated May 6, 1890.

Application filed January 23, 1890. Serial No. 337,830. (No model.)

To all whom it may concern:

Be it known that we, MORRIS PEAK and JAMES B. CASADAY, citizens of the United States of America, residing at Colorado Springs, in the county of El Paso and State of Colorado, have invented certain new and useful Improvements in Gate-Hangers; and we do hereby declare the following to be a full, clear, and exact description of the invention, 10 such as will enable others skilled in the art to which it appertains to make and use the same, reference being had to the accompanying drawings, and to letters of reference marked thereon, which form a part of this specification.

15 Our invention relates to hangers for gates; and it consists in the improved construction hereinafter described and set forth, whereby a simple and efficient hanger is provided that may be generally used where sliding gates 20 are desirable.

In the accompanying drawings, forming part of this specification, Figure 1 is a side view of a gate and our improved hanger; and Fig. 2 is a section on the dotted line xx , Fig. 1.

25 The parts A B, which are arranged on either side of the roadway and which in some instances will be constituted by the jamb of a door, carry, respectively, vertical loops $a a$ and horizontal eyes $b b$, the loops $a a$ being 30 located on the front of the post A, while the eyes $b b$ are on the inner side of the post B. The gate proper consists of uprights C D E and horizontal bars c , two of the latter projecting beyond the upright E at the front end 35 to engage the loops $a a$ and retain the gate against lateral swinging movement. Metal guideways d are located immediately beneath the top and third bars c , the ends of said guideways d bearing in the uprights C and D, 40 as indicated in Fig. 1.

The hanger proper consists of a metal strap G, made in a single piece, and bent at its upper end to present a yoke with depending por-

tions $f f$, in which bear the journals g of two rollers H H, grooved to receive the guideways 45 d above, and thus suspend the gate. The inner journals g are extended and looped to form eyes h , which register vertically with the eyes $b b$, so that a vertical rod i , headed at its upper end, can be dropped through both 50 sets of eyes, and not only support the hanger and gate suspended thereon, but form the pintle upon which the gate can turn when disengaged from the loops $a a$.

As the device is simple, its operation will 55 be apparent.

From the foregoing it will be obvious that the hanger is not only simple and composed of few parts, but presents an extended vertical support for the gate, and requires but few 60 connections to adjust it in operative position.

As will be readily understood, the hanger is adapted for use both in connection with barns or freight-cars, and can be so arranged as in no way to interfere with the door. 65

We claim—

The combination of a gate having bars c , a metal hanger independent of said gate and consisting of a strap in a single piece arched at its top to form depending separated free 70 end portions, rollers between and having their journals bearing in the same, the inner journals projecting beyond the strap and looped to form eyes, registering eyes bearing in a post B, and a rod dropped through both 75 sets of eyes to connect the hangers to the post and serve as a pintle for both hanger and gate, substantially as set forth.

In testimony whereof we affix our signatures in presence of two witnesses.

MORRIS PEAK.
JAMES B. CASADAY.
